(57) **CLAIM**

The ornamental design for an internal combustion engine, as shown and described.

DESCRIPTION

FIG. 1 is a front elevational view of an internal combustion engine showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front left high perspective view thereof;

FIG. 8 is a front left low perspective view thereof;

FIG. 9 is a rear left high perspective view thereof;

FIG. 10 is a front right high perspective view thereof; and,

FIG. 11 is a rear right high perspective view thereof.
